UNITED STATES PATENT OFFICE

122,523

DESIGN FOR A WRAPPER OR SIMILAR ARTICLE

Daniel B. Schwartzman, Jersey City, N. J.

Application January 25, 1940, Serial No. 89,705

Term of patent 7 years

To all whom it may concern:

Be it known that Daniel B. Schwartzman, a citizen of the United States and resident of Jersey City, in the county of Hudson and State of New Jersey, has invented a new, original, and ornamental Design for a Wrapper or Similar Article, of which the following is a specification, reference being had to the accompanying drawing, forming part thereof, and in which:

Fig. 1 is a perspective view of a wrapper embodying my new design;

Fig. 2 is a perspective view of the same, shown in position folded over articles placed therein;

Fig. 3 is a perspective view, similar to Fig. 2, but showing one flap opened up; and

Fig. 4 is a bottom plan view.

I claim:

The ornamental design for a wrapper or similar article, substantially as shown.

DANIEL B. SCHWARTZMAN.
